UNITED STATES PATENT OFFICE

107,278

DESIGN FOR A FLOOR MAT OR SIMILAR ARTICLE

Wallace G. Grossman and Howard Field Carpenter, White Plains, N. Y.

Application September 25, 1937, Serial No. 71,797

Term of patent 14 years

To all whom it may concern:

Be it known that we, Wallace G. Grossman and Howard Field Carpenter, citizens of the United States, residing in White Plains, New York, have invented a new, original, and ornamental Design for a Floor Mat or Similar Articles, of which the following is a specification, reference being had to the accompanying drawing, forming part thereof.

The drawing is a perspective view of a floor mat showing our new design.

We claim:

The ornamental design for a floor mat or similar article, substantially as shown.

WALLACE G. GROSSMAN.
HOWARD FIELD CARPENTER.
